MECHANICAL ERASER

Bruce Burns, Los Angeles, Calif.

Application August 15, 1947, Serial No. 768,724

10 Claims. (Cl. 129—36)

1 My invention relates to erasers for use generally in deleting marks, lines, letters and similar characters from typewritten and other sheets and from drawings. Specifically, the invention pertains to a mechanical eraser of a type wherein a long slender strip of eraser material is enclosed in a long barrel from which it may be intermittently fed as necessary to present additional eraser material as previously extended material is worn off in use.

Among the more important objects of the invention are the following:

To provide an eraser of such size and shape that it may be held in the manner of a pencil and used with substantially the same accuracy as a pencil;

To provide an eraser in which the erasing material is presented to the work in a relatively thin ribbon-like form so that it may be used to erase small areas such as individual characters in typewritten lines or individual lines adjacent other lines in drawings;

To provide an eraser which is particularly adapted to erasing single characters of typewritten material without removing the work from the typewriter and, if desired, without rotating the platen to move the work up into a more accessible position;

To provide an eraser in which practically all the erasing material may be efficiently used for the purpose of erasing without the necessity of cutting away and discarding or rubbing off portions of the material to keep the working edge sharp;

To provide an eraser from which the eraser material may be conveniently and rapidly extended as desired by a simple reciprocating action of a slider;

To provide an eraser in which the strip of eraser material is held firmly near the point of use so that elastic deflection is minimized;

To provide an eraser into which "refills" may be readily inserted with a minimum of difficulty and delay and to provide an eraser in which various grades of erasing material may be interchangeably used;

To provide an eraser in which the eraser material, except for the small exposed portion currently available for use, is completely enclosed and protected from accumulation of dirt, grease, perspiration, and other objectionable deposits; and

To provide an eraser incorporating a brush disposed on the end opposite the erasing end in

2 a form most convenient for cleaning erased material from the work.

Further objects of the invention will become apparent from the following specification and the drawing, which is intended for illustration purposes only, and in which:

Fig. 1 is a plan view of my improved mechanical eraser;

Fig. 2 is a side view of the same;

Fig. 3 is an enlarged fragmentary longitudinal sectional view of the forward end of the eraser, taken on line 3—3 of Fig. 1, but showing the eraser material as partially worn away;

Fig. 4 is a view similar to Fig. 3 showing the feeding slide as moved forwardly to project a new portion of the eraser material from the end of the device;

Fig. 5 is a similar view showing the eraser material as having been fed forwardly and the feeding slide returned to inoperative position;

Fig. 6 is an enlarged cross-sectional view, taken on line 6—6 of Fig. 5; and

Fig. 7 is an enlarged cross-sectional view, taken on line 7—7 of Fig. 5.

Referring to the drawing in detail, the improved eraser consists of four parts, namely, a barrel or holder 10, a slider or feeding element 11, a strip of eraser material 12 and a brush assembly 13.

The holder 10 consists of a tube of substantially rectangular cross section having its corners rounded as shown in Fig. 6. The holder 10 may be made from sheet metal struck up in a suitable die and folded to the required shape, after which the lateral edges of the stock may be secured in overlapping engagement as shown in Fig. 6. At its forward or "muzzle" end, the narrow sides of the holder 10 are slit as shown at 15 so as to provide upper and lower resilient tines or jaws 16 and 17. Rearwardly of the jaws 16 and 17, the wider top and bottom portions of the holder 10 are stamped with U-shaped cutouts 17', thus providing resilient tongues or retaining pawls 18 and 19 which curve inwardly as shown in Fig. 3. Preferably the holder member 10 is provided with a series of ribs 20 which serve as finger grips to prevent slipping of the holder between the fingers during an erasing operation or during feeding of the eraser material in the manner to be later explained.

The brush assembly 13, referred to above, comprises a sheet metal cup 22 in which the inner ends of a group of bristles 23 are clamped. The brush is applied to the rear end of the holder 10 by merely inserting the cup thereinto. As before

indicated, the brush is used for the purpose of cleaning erased material from the work, and it will be apparent that it also serves to cover the rear end of the holder so as to exclude dust and other foreign matter from the interior of the holder.

The slider or feeding element 11 consists of a rectangular tube having rounded corners and of a size adapting it to slide on the holder 10 at the forward end thereof. The slider may be made by blanking, embossing, and forming a sheet of thin metal into rectangular cross section, the lateral edges of the sheet being resistance-welded along the lapped seam. At the forward or "muzzle" end of the slider, the material is doubled or hemmed inwardly to form inwardly projecting lips 25, thus reducing the size of the opening at the forward end of the slider and reinforcing the thin flat-walled tube to provide greater stiffness. At the mid portion of the slider, its upper and lower sides have U-shaped cut-outs, thus providing resilient feeding pawls 26 and 27 which curve inwardly. Rearwardly of the pawls 26 and 27, the upper and lower sides of the slider are embossed to provide transverse ribs 28 which serve as finger-grips when the slider is moved longitudinally.

After the holder 10 and slider 11 have been fabricated, they are assembled by sliding the slider onto the muzzle end of the holder. During this movement, the pawls 26 and 27 are deflected outwardly by the jaws 16 and 17 and the upper and lower sides of the holder 10 until they pass the edges of the cut-out portions 17' in the upper and lower sides of the holder, at which time they spring inwardly into the cut-out portions 17'. The slider 11 may be pushed further onto the barrel 10 until it is finally restrained by contact of the inwardly projecting lips 25 against the forward ends of the jaws 16 and 17. The slider 11 is shown in substantially this position in Fig. 5, and it will be noted that engagement between the relatively rigid lips 25 and the readily deflectable jaws 16 and 17 forces the latter toward each other. After the slider 11 has been thus assembled on the barrel or holder 10, the pawls 26 and 27 act to prevent removal of the slider due to the fact that their forward ends move under the forward edges of the cut-outs 17'.

The eraser strip 12 is preferably made in parallelepipedal form with rounded or chamfered corners to give clearance inside the barrel 10. Rubber-base eraser stocks are commonly available in different types and grades for different kinds of work. For example, when erasing typed characters from hard bond papers, a hard and highly abrasive material is desirable; for erasing typed or carbon paper characters from soft bond or sulphite papers, a medium hard eraser stock with moderate abrasive qualities may be used; and for erasing pencil lines, a medium soft stock having mild abrasive qualities is suitable.

With the various parts of the complete device now described and with the slider 11 assembled on the barrel 10, the loading and feeding operations are performed as follows:

To insert an eraser strip 12, the brush assembly 13 is first removed from the rear end of the barrel 10, and the slider 11 is moved forwardly on the barrel 10 to the limiting position determined by contact of the pawls 26 and 27 with the edges of the cut-outs 17'. A length of eraser stock 12 is inserted into the rearward end or breech of the barrel 10 in which it slides freely until its forward end engages the inner surfaces of the tongues 18

and 19. Additional pressure exerted against the rearward end of the strip 12 forces it between the tongues 18 and 19 so that the forward end of the strip deflects and passes between these tongues until it comes into contact with the inner surfaces of the pawls 26 and 27. Due to the relatively poor columnar qualities of the eraser strip 12 under compression loads, and due to the tendency of the material to deflect into frictional contact with the inner walls of the barrel 10, it is usually impossible to extend the front end of the strip beyond the pawls 26 and 27 by applying further force against the rearward end of the strip.

At this time the barrel is held in one hand with the thumb and forefinger exercising a firm grip upon the ribs 20, and the slider 11 is grasped between the thumb and forefinger of the other hand and pulled rearwardly along the barrel until light resistance to further movement is caused by contact of the inwardly turned lips 25 against the jaws 16 and 17. During this rearward movement of the slider 11, the forward tips of the tongues 18 and 19, embedded in the eraser strip 12, restrain the latter from rearward motion which might be caused by contact of the tips of the pawls 26 and 27 against the strip 12.

With the slider 11 in retracted position, it is then firmly gripped between the thumb and forefinger of the operator so that the pressure applied to the outer surfaces of the pawls 26 and 27 forces the latter toward one another, and the tips of these pawls embed themselves in the flat upper and lower faces of the strip 12. With the pawls 26 and 27 thus firmly gripping the strip 12, pressure is maintained and the slider 11 is moved forwardly to the position shown in Fig. 4 where further movement is limited by contact between the pawls 26 and 27 and the edge of the cut-out 17'. This forward movement of the slider 11 will carry the eraser strip forward a distance approximately equal to that traveled by the slider itself. Pressure on the pawls 26 and 27 is then diminished so that the tips of these pawls are no longer embedded in the strip 12 and the slider is pulled back again to the position shown in Fig. 3. Pressure is then re-applied to the pawls 26 and 27 which re-embed themselves in the strip and the slider is again moved forwardly to the limit of travel. Three or four such successive reciprocal cycles will feed the strip forwardly until it projects beyond the end of the slider as shown in Fig. 4.

The slider is then pulled back onto the barrel firmly into the position of Fig. 5 and in this position pressure of the inwardly projecting lips 25 on the outer surfaces of the jaws 16 and 17 causes the latter to squeeze the strip 12 very firmly. The brush assembly 13 is inserted into the breech end of the barrel 10, and the completely assembled eraser is ready for use.

With eraser stocks such as previously referred to and having the approximate dimensions shown in the drawing a length of stock equal to about twice the thickness of the strip itself is left exposed when performing the initial loading operation. The eraser may be used until the projecting portion is worn off to a length of about $\frac{1}{16}$ ", or somewhat less than the thickness of the strip, as shown in Fig. 3. When it is desired to feed out additional eraser stock, the slider 11 is firmly grasped as explained before with inwardly deflecting pressure exerted on the pawls 26 and 27 and moved to the position shown in Fig. 4. A single such stroke will ordinarily feed out enough

eraser stock to replace that worn off and the slider 11 may then be returned to the gripping position of Fig. 5. If by any chance a single stroke of the slider does not feed out as much stock as desired, supplementary strokes may be employed.

As more and more eraser material is successively extended and worn off, the strip 12 is progressively moved forwardly until the tips of the pawls 26 and 27 push against the rearward end of the strip. This is the limit of "automatic" feeding, and at this time the remaining strip of eraser stock is approximately $\frac{1}{2}$ " long. As the extended end of this remaining portion is worn down, some additional material may be extended by pulling on the exposed end, so that only a sufficient length of material to permit firm grip by the jaws 16 and 17 (approximately $\frac{1}{8}$ ") finally remains as unusable waste. It will be seen that this permits up to 95% utilization of the eraser material.

If it is desired to change the "load" from one type of eraser stock to another, this may be easily done in the following manner: With a normal projecting length of eraser material extended from the muzzle, the slider 11 is moved back and forth a few times to increase this length and brought to rest in a position near the forward position. Pressure of thumb and forefinger is then released, with the result that the pawls release their grip upon the eraser strip. The projecting end of the strip is then grasped and the entire strip withdrawn from the barrel. The substitute eraser material may then be loaded and fed into position for use as previously described.

In contrast to prior erasers, the eraser of my design has marked advantages. The slender but rigid metallic barrel gives the typist a firm grip which permits manipulation of the short extended portion of eraser stock in contact with the work with precise pressure and accuracy. Both longitudinal and transverse erasing operations may be performed with relative ease and precision. By far the most common typing error is one of a single letter in a word and since the thickness of the extended portion (.094") of the eraser is of the same order as the spacing of pica and elite types, transverse erasure of single characters is accomplished with accuracy and ease. As the eraser is held in one particular position relative to the work for a few strokes and eraser material is worn off, relatively sharp corners are produced on the projecting piece of stock and with a change in grip on the barrel these corners may then be utilized to furnish small areas for further accurate erasing operations. As these corners, in turn, wear down, others are produced for further "small area" erasure. With a little practice a typist can perform numberless consecutive erasing operations with great accuracy without any necessity for "sharpening" the eraser and with full utilization of the material for constructive erasing.

When it is necessary to erase at or near the bottom of a typed page, under such conditions that it would be undesirable to move the platen, the eraser of my design is very superior. By moving the typewriter carriage to one side or the other, the typist can bring the error into view, and by taking advantage of the slenderness, length and rigidity of my eraser she may erase either longitudinally or transversely. Since the platen is not rotated, register is intact and erased areas may be immediately re-typed. The fact

that the present eraser may be used with great accuracy largely eliminates the need for using an erasing shield, and in turn eliminates the smudging difficulty previously pointed out. The facts that in the eraser of my design the hands never come into contact with the eraser material and the strip of material is completely enclosed except for the short projecting section made available for current use result in having very clean and grease-free material at the point of application to the work, with consequent elimination of smudging due to foreign matter.

In addition to the manifest advantages of the eraser of my design for use on typewritten material, it is very useful for erasure of hand written or hand drawn pencil or ink lines. When used with certain eraser stocks, previously mentioned, the improved device will erase ink lines with great accuracy, and when loaded with other material it makes an excellent tool for draftsmen. On the drafting board, as well as on typewritten material, an erasing shield may leave marginal smudges; since my eraser may be used with extreme accuracy without a shield, this difficulty is eliminated. Not infrequently a draftsman will inadvertently draw a full or solid line where a broken or dotted line is called for. With ordinary equipment, the corrective procedure is to completely erase the incorrect line and re-draw it. With the eraser of my design, it is only necessary to erase short lengths of line at intervals as desired, thus producing the required interrupted line. Since the instrument can be handled with substantially the rapidity and accuracy of a pencil, an operation of this sort can often be carried out with a material saving of time over the ordinary method.

While I have herein shown and described the improved eraser device as embodied in a preferred form of construction, by way of example, it will be apparent that various modifications might be made in the structure without departing from the spirit of the invention. Consequently I do not wish to be limited in this respect but desire to be afforded the full scope of the appended claims.

I claim as my invention:

1. An erasing device, including: a tubular holder of substantially rectangular cross section; an eraser strip of similar cross section slidable in said holder; manually operable, one-way feeding means slidable on said holder and successively engageable with portions of said strip within said holder for feeding successive portions of said strip from said holder; and flexible means on said holder engageable by said feeding means and adapted to be flexed thereby into engagement with said strip for preventing reverse movement of said strip.
2. An erasing device, including: a tubular holder of substantially rectangular cross section; an eraser strip of similar cross section slidable in said holder; manually operable, one-way feeding means reciprocable on said holder and engageable with different portions of said strip during successive reciprocations of said feeding means so as to feed an end of said strip predetermined increments of movement in one direction from an end of said holder; and resilient means on said holder engageable by said feeding means and adapted to be flexed thereby into engagement with said strip so as to prevent reverse movement of said strip.
3. A device as defined in claim 2 in which said feeding means consists of a slider slidable on said

holder and having resilient pawls engageable with opposite sides of said strip to feed the same in one direction when said slider is slid in said one direction, said pawls being adapted to slide along said strip in the opposite direction when said strip is held against movement in said opposite direction by said resilient means, said pawls overlying said resilient means upon reaching the limit of movement of said slider in said opposite direction.

4. A device as defined in claim 3 in which said holder has openings through which said pawls extend to engage said strip.

5. An erasing device, comprising: a tubular holder of substantially rectangular cross section, said holder having openings in its wider sides and resilient tongues projecting inwardly from said sides; an eraser strip of similar cross section slideable in said holder; and a slider reciprocal longitudinally on said holder and having resilient pawls extending through said openings and engageable with said strip to feed the same predetermined increments during successive movements of said slider in one direction so as to project said strip from an end of said holder, said pawls being adapted to slide relative to said strip when said slider is moved in the opposite direction, said tongues being adapted to engage said strip to prevent reverse movement thereof during movement of said slider in said opposite direction, said pawls overlying and depressing said tongues into firm, unyielding engagement with said strip when said slider reaches the limit of its movement in said opposite direction so as to cause said tongues to effectively retain said strip in its projected position when the erasing device is applied to use.

6. An erasing device, comprising: a tubular holder of substantially rectangular cross section, said holder having openings in its wider sides and resilient tongues projecting inwardly from said sides; an eraser strip of similar cross section slideable in said holder; and a tubular slider surrounding said holder and reciprocal longitudinally on said holder and having resilient pawls extending through said openings and engageable with said strip to feed the same predetermined increments during successive movements of said slider in one direction so as to project said strip from an end of said holder, said pawls being adapted to slide relative to said strip when said slider is moved in the opposite direction, said tongues being adapted to engage said strip to prevent reverse movement thereof during movement of said slider in said opposite direction, said pawls overlying and depressing said tongues into firm, unyielding engagement with said strip when said slider reaches the limit of its movement in said opposite direction so as to cause said tongues to effectively retain said strip in its projected position when the erasing device is applied to use.

7. An erasing device, comprising: a tubular holder of substantially rectangular cross section, said holder having openings in its wider sides and resilient tongues projecting inwardly from said sides; an eraser strip of similar cross section slideable in said holder; a tubular slider surrounding said holder and reciprocal longitudinally on said holder and having resilient pawls extending through said openings and engageable with said strip to feed the same predetermined increments during successive movements of said slider in one direction so as to project said strip from an end of said holder, said pawls being adapted to slide relative to said strip when said slider is moved in the opposite direction, said tongues being adapted to engage said strip to prevent reverse movement thereof during movement of said slider in said opposite direction; and stop means on said holder engageable with said slider for limiting the extent of reciprocal movement of said slider, said pawls overlying and depressing said tongues into firm, unyielding engagement with said strip when said slider reaches the limit of its movement in said opposite direction so as to cause said tongues to effectively retain said strip in its projected position when the erasing device is applied to use.

8. A device as defined in claim 5 in which said holder is provided with resilient jaws at its end from which said strip is projected, said jaws being adapted to engage opposite sides of said strip when flexed toward each other, said slider being engageable with said jaws to flex the same.

9. A device as defined in claim 5 in which said holder is provided with resilient jaws at its end from which said strip is projected, and said slider is provided with inturned lips engageable with and adapted to depress said jaws into firm engagement with said strip when said slider is moved in said opposite direction.

10. A device as defined in claim 5 in which said tongues project in said one direction within said openings in alignment with said pawls so that movement of said slider in said opposite direction causes said pawls to ride up on said tongues to force said tongues into firm engagement with said strip.
